UNITED STATES PATENT OFFICE

2,471,471

APPARATUS FOR SIMULTANEOUSLY INDUCTIVELY HEATING A PLURALITY OF ARTICLES

Alden O. Wood, Parma, Ohio, assignor to The Ohio Crankshaft Company, Cleveland, Ohio, a corporation of Ohio

Application March 9, 1945, Serial No. 581,854

7 Claims. (Cl. 219—13)

1

The present invention relates as indicated to parallel multiple inductors and is concerned primarily with inductors having a plurality of work-receiving openings disposed to heat several articles equally and simultaneously. In Patent No. 2,271,916, issued February 3, 1942, and owned by the assignee of the present application, an inductor is shown and described which is capable of such equal and simultaneous heating. When several relatively large articles are to be heated the inductor shown in the patent becomes long, is somewhat difficult to support and requires considerable space making it necessary to provide special means for its use. It is usually desirable to keep the work-receiving openings equal in size to simplify the manufacture of the inductor and arrange these openings in a compact form to improve convenience of use. The present invention is concerned chiefly with meeting these requirements as to ease of manufacture, convenience of use, and equality of heating.

Accordingly, the chief object of the present invention has been to provide a multiple hole inductor having substantially equal work-receiving openings. Another object has been to provide such inductor with openings compactly and symmetrically arranged. An additional object has been to provide an inductor having conductors for supplying the inducing current so disposed as not to disturb heating at any of its several heating stations. A further object has been to provide means for substantially independently cooling the portion of the inductor at each heating station. A further object has been to provide means for moving several articles simultaneously into corresponding inductors.

Other objects will become apparent from the following description and from the accompanying drawings which illustrate one form of my improved apparatus.

In the drawings:

Fig. 1 is a plan view showing the general form of inductor and the means for moving the work pieces into the inductor openings;

Fig. 2 is an elevation taken as indicated at 2—2 of Fig. 1 and showing the inductor only;

Fig. 3 is an elevation partly in section taken as indicated at 3—3 of Fig. 1;

Fig. 4 and 4A show the construction of the upper ends of the pins for supporting and locating the work pieces; and,

Figure 5 shows an inductor of modified construction embodying the present invention.

In the form of the apparatus illustrated provision is made for heating four articles simul-

taneously, the articles being supported in inductors 10, 11, 12, and 13 with properly selected clearances. Current of correct frequency is supplied by a suitable source 14 to terminals 15 and 16. This current, if assumed to enter through terminal 15 passes in parallel through inductor members 17 and 18 which may be individual members as shown or combined into one member. The current through member 17 passes circumferentially around inductor loop 10 and that through member 18 passes around loop 11. It then passes through members 20 and 21 respectively in parallel and then passes circumferentially around inductor loops 12 and 13 returning to the source 14 through inductor member 24 and terminal 16. When loops 10 and 12 have the same sectional areas and encircle articles identical with the articles encircled by loops 11 and 13 current in all of the four loops is the same and heating in all loops is equal.

To carry away the inductor power loss and to thus maintain maximum conductivity with a minimum amount of copper and to thus insure uniform operation, an abundance of cooling water is supplied individually to each inductor loop to insure low inductor temperature. Water for loops 10 and 11 is supplied through passages 26 and 27 respectively in terminal 15 and that for loops 12 and 13 is supplied by passages 29 and 30 through terminal 16 and member 24. Each loop has its individual water outlet. Fittings 32 and 33 serve as outlet passages for water from loops 10 and 11 respectively and fittings 35 and 36 serve as corresponding outlet passages for loops 12 and 13.

Fig. 3 illustrates the apparatus for elevating into the inductor loops, the parts, such as bearing races 35, which are to be heat treated. This elevating apparatus is carried on the floor of quenching tank 38 which in turn is supported by any suitable means. This apparatus comprises a vertically moveable platform 40 having four groups of three pins each such as 41, each group of pins corresponding in location with each inductor loop. The three pins of each group are disposed triangularly, each pin of each group being a vertex of a generally equilateral triangle. The upper end of each pin is machined to provide a supporting ledge having an ledge 45 to engage a lower side of a bearing race and hold the race at correct elevation and to provide a vertical face with an edge 46 to engage an inner peripheral surface of the bearing race to center the race in the corresponding inductor loop. These pins are of relatively small diameter to

reduce to a minimum the heat generated in them when the races are being heated.

Platform 40 which carries pins 41 supporting the race to be hardened is attached to plate 50 which is carried by elevator 51 and spaced therefrom by members 52 and 53, through bracket 55. The elevator is supported by piston rod 56. This piston rod is actuated by a piston in cylinder 58. To insure that the elevator moves in a straight line, guide rods 60 and 61 are provided which pass through suitable clearance holes in bracket 55 and one of them passes through lower support 62 which is also attached to the elevator.

Fluid to operate the piston is supplied to cylinder 58 by means of suitable piping. Fluid supplied by piping 63 raises the elevator by forcing the piston upwardly and fluid from piping 64 forces it down providing rapid and positive movement of the elevator in both directions. A four-way valve 65 controls the supply of fluid and is 15 usually operated by a timer-controlled solenoid 66.

In operation the bearing races or other articles to be heat treated are manually placed on pins 41 and power is applied for an interval of time usually regulated by a timer, to heat the race. The timer then interrupts the power supply and by its supply of current to solenoid 66 operates valve 65 to rapidly lower elevator and plunge the races into a quenching medium in tank 36. After a predetermined quenching interval platform 40 is again raised by further timed operation of valve 65 and the races are removed and replaced by other races to be heat treated.

Numerous modifications may be made in the details of the apparatus such, for instance, as combining conductors 17 and 18 into one conductor with a single water passage therethrough. The inductor loops may be attached directly to the conductors, such as loop 10 being joined to conductors 17 and 20 with members 70 and 71 greatly reduced or eliminated and the width of space 72 therebetween may be varied. The inductor loops may be of any desired form to accommodate the part to be heated, but are always disposed to bridge the space between members such as 70 and 71 or between adjacent ends of conductors such as 17 and 20. The number of inductor loops may be increased or decreased as desired and these may be variously arranged along the connecting conductors. Thus, in Figure 5, there is shown an inductor having a total of six inductor loops 10' arranged in groups of three in series and the groups of three being connected in parallel. Further, it is not necessary that the loops be disposed oppositely as shown, but may be arranged in staggered formation along the supply conductors.

Other forms may be employed embodying the features of my invention instead of the one herein explained, change being made as regards the means and the steps herein disclosed, provided the elements or steps stated by any of the following claims or the equivalent of such stated elements or steps be employed.

I therefore particularly point out and distinctly claim as my invention:

1. In apparatus of the class described, a multiple inductor comprising a pair of substantially parallel conductors defining a plane, each conductor comprising an inductor loop in series therewith, axes of the loops being in generally parallel spaced positions and perpendicular to the plane of the conductors, the loops being on generally opposite sides of the pair of conductors and being disposed to substantially encircle metallic articles

lying in generally parallel positions, the pair of conductors having a common return circuit conductor lying generally parallel to the said pair of conductors but remote from the articles to be heated, and means for supplying inducing current to the pair of conductors to flow in parallel therethrough to heat simultaneously two of the said articles being encircled by the aforesaid loops.

2. In apparatus of the class described for simultaneously and equally heating a plurality of metallic articles, an inductor comprising two generally parallel conductors, each conductor comprising an inductor coil bridging a cut in said conductor and being adapted to be electrically coupled to an article to be heated, the parallel conductors having a common return circuit conductor lying in generally close parallel relation with generally straight portions of said parallel conductors and remote from the coils.

3. In apparatus of the class described for heating surface zones of a plurality of articles in a limited space, a pair of generally parallel and closely spaced supply conductors, each supply conductor comprising a plurality of inductor coils adapted to serve as inductors to heat the articles when the articles are in the coils, the coils being disposed generally on opposite sides of the pair of parallel conductors and lying substantially in the plane of said conductors, means for flowing current in parallel through the supply conductors, the inductor coils of each conductor being in series, and a return conductor lying in closely spaced parallel relation with the supply conductors and remote from the coils to neutralize inductive heating by current in the parallel parts of the supply conductors substantially without affecting heating in the coils.

4. In apparatus for simultaneously heating a plurality of metallic articles a circuit comprising three closely spaced generally parallel conductors extending generally away from and being connected to a source of inducing current, two of said conductors comprising a delivery branch and the other conductor being a return branch of the circuit, each conductor of the delivery branch having a plurality of openings, and current conducting coils bridging the openings and extending generally laterally from the conductors, the said coils serving as inductors for heating the aforesaid articles and lying substantially out of magnetic fields of the parallel conductors.

5. In an inductor for simultaneously heating a plurality of metallic articles, two pairs of inductor coils, each coil being disposed generally in a corner of a square, conductors connecting the coils of each pair in series, a supply conductor and a return circuit conductor connecting the pairs of series coils in parallel and to a common source of inducing current, said return circuit conductor lying in close parallel relation with the conductors connecting the coils.

6. In an inductor for simultaneously heating a plurality of metallic articles, a plurality of inductor coils, said coils being arranged in a plurality of groups, conductors connecting the coils of each group in a series electrical relationship, the groups being arranged in parallel electrical relationship, a supply conductor and a return-circuit conductor connecting the parallel connections of the groups to a common source of inducing current, said return-circuit conductor lying in close parallel relationship with the con-

ductors connecting the coils of each group in series.

7. In apparatus for simultaneously heating a plurality of metallic articles, a circuit comprising at least a pair of closely-spaced, generally-parallel conductors extending generally away from and being connected to a source of inducing current, at least one of said conductors comprising a delivery branch and at least one of the other conductors comprising a return branch of the circuit, said delivery-branch conductor having a plurality of openings and current-conducting coils bridging the openings and extending generally away from said conductors, the said coils serving as inductors for heating the aforesaid articles and lying substantially out of magnetic fields of the parallel conductors.
